ANGULAR PIERCING TOOL

Neil B. Granberg, Milwaukee, Wis., assignor to
 A. O. Smith Corporation, Milwaukee, Wis., a
 corporation of New York

Application February 2, 1948, Serial No. 5,745

2 Claims. (Cl. 164—86)

1

This invention relates to punch presses and the like and particularly to apparatus for riveting or punching holes angularly to the stroke of the press.

An object of the invention is to provide an apparatus which is easily and quickly set up for use with a standard press to operate singly or simultaneously with other work operations of the press and which is simple and economical to construct.

Another object is to provide an angular piercing or riveting tool having a push rod which is not mechanically fastened to the press punch and which, therefore, need not be accurately machined or aligned for assembly with the press.

Another object is to provide a floating drive connection between the press and the angularly directed punch to eliminate expensive machine parts.

Another object is to provide a punch press assembly which is readily set at various positions without realignment with the driving members.

These and other objects and advantages of the invention will appear hereinafter in connection with the following description of an embodiment of the invention, as illustrated in the accompanying drawings.

In the drawings:

Figure 1 is a front elevation of the tool showing the punch holder in its raised or retracted position with parts being shown in section;

Fig. 2 is a side elevation of the assembly of Figure 1;

Fig. 3 is a front elevation of the tool with the punch holder advanced to its lower position;

Fig. 4 is a view similar to Fig. 3 but with the punch at the end of its working stroke; and

Fig. 5 is an enlarged detail sectional view of the punch and its adjacent parts, shown in the same position as in Fig. 4.

The invention comprises, in general, a base 1 supporting the die 2, an upper plate member or platen 3 which is adapted to be secured to the press, not shown, and to move upwardly and downwardly therewith, and an intermediate stripper bar member 4 supporting the punch 5 and operating mechanism therefor.

Base 1 and members 3 and 4 are of substantial thickness and of sufficient length to accommodate, on either side of the punch, guide pins 6 which extend downwardly from member 3 near opposite ends thereof and through holes 7 aligned therewith in member 4. Tubes 8 extend upwardly from base 1 in alignment with holes 7 to provide bearings for the lower ends of pins 6. Tubes 8 receive the guide pins 6 and thereby op-

pose the side thrust of the tool when the punch is operated, as will be described.

Bosses 9, which are of the same diameter as tubes 8, project downwardly from member 4 in alignment with tubes 8 and engage tubes 8 to limit the downward positioning movement of the punch carried by said member 4.

Bosses 10 are disposed on the underside of upper plate member 3 to provide sockets of substantial depth for attachment of guide pins 6 to the plate. Two spaced rods 11 are secured to member 3 and extend downwardly through member 4. Rods 11 are threaded at their upper ends for threading the same into member 3 and are provided with heads 12 at their lower ends. The rods 11 are provided to lift the punch assembly during the return stroke of the press after the withdrawal of the punch from the work, as will be described.

20 A die block 13 is welded or otherwise secured to the base 1. Die 2 is seated in block 13 at the desired angle and location to receive punch 5.

A tubular punch support 14 integral with member 4 carries punch 5 at the desired angle and in alignment with die 2 when the member 4 is in its lowered position. Punch support 14 may be welded to the underside of plate 4 or may be cast therewith. A bushing 15 within the lower end of tube 14 supports the punch 5 and allows free longitudinal movement thereof in the tube. A snap ring 16, seated in an annular groove 17 in tube 14, secures bushing 15 within the tube.

An annular member 18 is welded to the end-plate 19 at the lower end of the tube 4 and serves as a stripper for the punch which extends therethrough, and as a hold-down for the work.

A bore 20 extends through the tube 14 and the plate 4 for receiving the punch.

A spring 21 is disposed in the bore 20 encircling punch 5 and between the bushing 15 and a head 24 on the upper end of the punch to bias the latter upwardly. A rod 22 extends upwardly in bore 20 from head 24 and universally supports a push rod 23 which in turn extends upwardly into a recess in platen 3.

In operation, the punch 5 is moved downwardly against the biasing action of a spring 21 by a pair of rods 22 and 23 actuated by the upper movable plate member 3. The lower rod 22 is disposed in bore 20 in intermediate plate 4 and tube 14. A cap 24 fits over the upper end of punch 5 beneath rod 22 and is secured to the punch 5 by means of a set screw 25. The cap 24 supports the upper end of punch 5 within the bore 20 and provides a shoulder 26. The spring 21, encircling

the punch 5, is interposed between the bushing 15 and the shoulder 26 to bias punch 5 and rod 22 upwardly to maintain contact with rod 23 and platen 3.

The upper end of lower rod 22 projects from hole 20 above plate 4 and is spherical in shape to fit within a conical-shaped recess 27 in the lower end of rod 23.

The upper end of rod 23 is spherical and is seated in a cone-shaped recess 28 in the lower surface of member 3. A neoprene gasket 29 serves to retain rod 23 within the recess.

In the downward stroke of the press, the punch assembly moves downwardly with upper plate 3 until the bosses 9 of intermediate member 4 reach the guide tubes 8 extending upwardly from base 1 at which time punch 5 is in alignment with die 2 and the hold-down member 18 is adjacent the work. As the upper member 3 continues to move downwardly, the rods 23 and 22 push the punch downwardly in tube 14 to effect the angular working stroke.

In the return stroke of the press, the upper member 3 is raised and spring 21 biases punch 5 upwardly within tube 14 to retract the punch from the work with the member 18 acting as a stripper to strip the work from the punch. The heads 12 of rods 11 then engage member 4 and lift the entire punch assembly away from the base 1 and die 2.

The punch assembly is easy to adjust and set up for different work and does not require periodic adjustments to maintain the punch in alignment with the die.

The tool is easily adapted for use with any press and is simple and inexpensive to construct of standard materials. The tool may be employed as a punch or as a riveting instrument.

Various embodiments of the invention may be employed within the scope of the accompanying claims.

I claim:

1. A tool assembly of the class described, comprising a die for supporting a workpiece, a platen disposed to move bodily toward and away from the workpiece in the cycle of a punching operation, an intermediate platen disposed between said first named platen and said die and disposed to move in the direction of movement of said first named platen, a punch unit carried by said intermediate platen with the punch thereof disposed to move at an acute angle to the direction of movement of said intermediate platen and toward and away from the workpiece, means to limit the movement of said intermediate platen toward the work short of completion of the movement of said first named platen toward the work and at a position of alignment between said punch and die, means connecting said platens to effect carriage of said second platen by said first

platen and having a lost motion to provide for continued movement of said first platen after said second platen is stopped by said limiting means, and means carried by said first named

5 platen and universally engaging said punch to force the same angularly toward the workpiece upon continued movement of said first named platen after the intermediate platen has reached the limit of its movement toward the workpiece.

2. A tool assembly of the class described, comprising a die for supporting a workpiece, a platen disposed to move bodily toward and away from the workpiece in the cycle of a punching operation, an intermediate platen disposed between said first named platen and said die and disposed to move in the direction of movement of said first named platen, means to carry said intermediate platen by said first named platen and providing lost motion therebetween whereby said 10 first named platen has a longer movement than said intermediate platen in the cycle of a punching operation, a punch unit carried by said intermediate platen with the punch thereof disposed to move at an acute angle to the direction of 15 movement of said intermediate platen and toward and away from the workpiece, means to limit the movement of said intermediate platen toward the work short of completion of the movement of said first named platen toward the 20 work and at a position of alignment between said punch and die, and a push rod disposed between said first named platen and the upper end of said punch and universally movable with respect to each whereby the punch is forced angularly to 25 toward the workpiece upon contained movement of said first named platen after the intermediate platen has reached the limit of its movement toward the workpiece.

NEIL B. GRANBERG.
